Attorney

UNITED STATES PATENT OFFICE.

JOHNSON R. BAKER, OF WYOMING, PENNSYLVANIA.

ARTICLE-WRAPPER.

1,355,804.

Specification of Letters Patent. Patented Oct. 19, 1920.

Application filed February 12, 1918. Serial No. 216,716.

To all whom it may concern:

Be it known that I, JOHNSON R. BAKER, a citizen of the United States, residing at Wyoming, in the county of Luzerne and State of Pennsylvania, have invented certain new and useful Improvements in Article-Wrappers, of which the following is a specification.

This invention relates to new and useful improvements in article wrappers, and the primary object of the invention is to provide a simple and efficient means for securely wrapping articles to be mailed which are not required to be sealed.

Another object of the invention is to provide an article wrapper of this character which is formed of a single piece of material so formed that the same is adapted to securely engage the article and hold the same therein in such a manner that there is no likelihood of accidental opening of the wrapper when the same is once securely positioned.

A further object of the invention is to provide a device of this character which is easily and simply constructed, inexpensive to manufacture, and one which will be very efficient in operation.

With these and numerous other objects in view, my invention consists of the novel features of construction, combination and arrangement of parts which will be herein referred to and more particularly pointed out in the specification and claim.

35 In the accompanying drawings:

The figure illustrates a plan view of the blank from which the wrapper is formed.

In describing my invention, I shall refer to the drawings in which similar reference characters designate corresponding parts throughout the several views.

The wrapper is formed from a single sheet of material, preferably paper, rectangular in outline and with spaced clefs 6 and 7 in two opposite edges.

45 The sheet is adapted to be folded along the dotted lines 4, 5, 8, and 9 to form a front or body 10, side flaps 11 and 12, and end flaps 2 and 3 to the front 10, end flaps 13 and 14 to the side flap 12, and the end flaps 16 and 17 to the side flaps 11.

The folds along the lines 8 and 9 are in alinement with the clefs 6 and 7 while the folds between the end flaps and the front

and the side flaps are in alinement with the inner terminals of the clefs.

When the device is to be used the article to be inclosed is disposed upon the front portion 10, the article being of substantially the same size as the latter, one of the side flaps, 60 for instance the flap 11, folds thereover and the end flaps 16 and 17 "tucked in" between the front or body and the inclosed article. The other side flap 12 is then folded over the previously folded side flap 11 and the end flaps 13 and 14 "tucked in" between the previously tucked in flaps 16 and 17 and the front 10.

70 The end flaps 3 and 2 of the front 10 are then preferably tucked in between the previously tucked in flaps 13 and 14 and the front 10. This novel arrangement of the wrapper over the article will securely hold the same in position and prevent its accidental disengagement.

75 This type of wrapper is especially adapted for use in mailing articles such as advertising matter or the like which it is not required to seal. The front portion 10 may be used to contain the address and the wrapper forms a combined envelop and holder. Owing to the fact that the wrapper is formed of a single piece of material it may be economically manufactured and no adhesive or any other fastening elements are employed 80 other than the simple tucked in flaps heretofore described. This novel arrangement is sufficient to securely hold the article wrapped during its transmittal and will absolutely prevent any accidental disengagement.

90 From the foregoing description taken in connection with the accompanying drawings, it is thought that a clear and comprehensive understanding of the construction, operation, and advantages of my invention 95 may be had, and while I have shown and described the device as embodying a specific structure, I desire that it be understood that such changes may be made in said structure as do not depart from the spirit and scope of the invention as claimed.

100 Having fully described my invention, what I claim is new, and desire to secure by Letters Patent, is:

105 A wrapper of the class described formed from a sheet of material with relatively short clefs in spaced relation in the ends, whereby correspondingly short end flaps are

produced, the sheet being foldable along lines between the confronting ends of the clefts and in alignment therewith to form side flaps, and the end portions of the sheet foldable along the lines even with the inner ends of the clefts to form short end flaps respectively to the front portion and to the side flaps, and the side flaps overlapping

the front portion to form a receptacle for an object, and the shorter end flaps tucked in to retain the contents of the wrapper without preventing inspection thereof. 10

In testimony whereof, I affix my signature hereto.

JOHNSON R. BAKER.
